VACLAV PRAJER, OF GARDNERVILLE, NEVADA

DRILL AND PIPE PULLING MACHINE

Application filed November 10, 1928. Serial No. 318,453.

This invention relates generally to drilling apparatus and has particular relation to means for pulling machine drills or bull picks, etc., out of holes in rock or ground, should the drills or picks become stuck or work hard; or for pulling pipes without injury to the latter.

Another object of the invention is the provision of a pulling apparatus which is simple in construction, may be quickly positioned for use, and by means of which drills or pipe may be pulled upward, either by turning the same, or directly upward without permitting the drill or pipe to turn.

With the above and other objects in view, the invention further includes the following novel features and details of construction, to be hereinafter more fully described, illustrated in the accompanying drawings and pointed out in the appended claims.

In the drawings:

Figure 1 is a vertical sectional view of a pulling apparatus constructed in accordance with the invention and shown in position for use.

Figures 2 and 3 are sections taken respectively on the lines 2—2 and 3—3 of Figure 1.

Figure 4 is a fragmentary elevation showing a slightly different form of the invention.

Figure 5 is a vertical sectional view of the subject matter of Figure 4.

Figure 6 is a section on the line 6—6 of Figure 4.

Figure 7 is a detail top plan view of the sleeve.

Figure 8 is an elevation partly in section showing a modified form of the invention.

Figure 9 is a plan view of the center bearing member shown in Figure 8.

Figure 10 is a bottom plan view of the lower bearing member shown in Figure 8.

Figure 11 is a sectional view on the line 11—11 of Figure 8.

Figure 12 is a fragmentary elevation showing a further slightly modified form of the invention.

Referring to the drawings in detail wherein like characters of reference denote corresponding parts, the reference character 10 indicates a stand which is shown as cylind-

rical in shape and provided with a longitudinal bore having threads 11 therein. Extending downwardly from the stand are anchors 12 whose upper ends are received within recesses 13 provided in the stand, while threaded studs 14 serve to hold these anchors in place. Reinforcing webs 15 are provided above the anchors. As shown in Figure 1 of the drawings, the anchors are positioned within the ground around the hole 16 from which the drill or pipe is to be pulled.

Positioned within the stand 10 is a sleeve 17 and this sleeve is externally threaded as shown at 18 for engagement with the threads 11, so that when the sleeve is rotated it will be moved longitudinally of the stand. The sleeve 17 is formed with a circumferentially and laterally disposed arcuate opening 19 and mounted within this opening for swinging movement upon a hinge pin 20 is a clamping member 21 and this has thereon a headed member 21' forming a finger knob for the convenient opening of the same. The inner face of this clamping member is provided with gripping elements 22 and is held in gripping position by means of pins 23. These pins extend downwardly through the head 24 upon the upper end of the sleeve and within which the opening 19 is located. A binding screw 25 extends radially inward through the head. The head is also provided with radially disposed openings 26 for the reception of operating bars 27, the latter being preferably attached to the head through the medium of chains 28.

In the use of the invention, the stand is placed over the hole 16 with the anchors 12 embedded in the ground, the clamp 21 first being released and swung outward and the screw 25 screwed outward. This permits the drill 29 and its collar 30 to pass through the bore. The clamp 21 is then closed and held in closed position by the pins 23, after which the binding screw 25 is adjusted to engage the drill. The bars 27 after being inserted within the openings 26 are utilized to rotate the sleeve 17 whereupon the drill will be pulled upward. In Figures 4, 5, and 6, the drill 26 may be pulled without rotating said drill. For this pur-

pose, the head 24 of the sleeve 17 has mounted thereon a bearing member 31 which is provided with concentric grooves 32 in its upper face. A central or intermediate bearing member 33 is mounted upon the bearing member 31 and is provided with concentric ribs which are received within the grooves 32. The bearing member 33 is formed of semi-circular sections as shown in Figure 9 and its upper face is provided with concentric grooves 34 which receive similarly arranged ribs 35 provided in an upper bearing member 36. This last referred to bearing member is provided with radially disposed grooves 37 in its upper face and these grooves are adapted to receive ears 38 which extend from semi-circular gripping members 39. These gripping members are clamped about the drill 26 by means of clamping bolts 40. 20 By the construction just described, when the sleeve 17 is rotated through the medium of the bars 27, the gripping members 39 which are engaged with the drill will not rotate due to the relative movement of the bearing members 31 and 33 so that the drill will be pulled directly upward.

In the form of the invention shown in Figure 8, the head 24 of the sleeve 17 is provided with radially disposed recesses 41. 30 These recesses communicate with the bore of the sleeve 17 and are adapted to receive ribs 42 which extend longitudinally of segmental gripping members 43. These gripping members are adapted to engage opposite sides of 35 a pipe 44 to be pulled and are held in position by means of set screws 45. The gripping members 43 thus prevent the set screws from injuring the pipe. In this form of the invention, the bottom bearing member 31a is provided with diametrically disposed notches 46 which receive the upper ends of the ribs 42. The pipe may also be engaged by the gripping members 39 which are mounted upon the top bearing members 36 with the 45 center bearing member 33 interposed between the top bearing member and the bottom bearing member 31a.

Instead of using the anchor members 12, spikes or rods 47 may be driven into the 50 ground through openings provided in the stand.

In Figure 12, the head 24 of the sleeve 17 is provided in its top with a radially disposed groove 48 which receives the ears 38 of the 55 clamping member 39 which is adapted to grip the drill 26. By rotating the sleeve 27 in the manner previously described, the drill 26 will be rotated and drawn upward.

It is preferable with this form of the invention that the threads of the sleeve and the stand be reversed.

The invention is susceptible of various changes in its form, proportions and minor details of construction and the right is herein reserved to make such changes as properly

fall within the scope of the appended claims.

Having described the invention what is claimed is:

1. In an apparatus of the kind described, an anchored stand having a threaded longitudinal bore, a sleeve adjustably engaging the threaded bore and having an opening extending for a distance circumferentially thereof and laterally, a clamping member coextensive with the opening and pivoted at one end for swinging movement, gripping means on the inner side of said member to confront and bite a drilling tool when within the sleeve, means for holding the said clamping member within the opening, and a binding element mounted in the sleeve diametrically opposite the clamping member to coact with the gripping means for forcing these in biting engagement with the drilling tool. 70 75 80

2. In an apparatus of the kind described, an anchored stand having a threaded longitudinal bore, a sleeve adjustably engaging the threaded bore and having an opening extending for a distance circumferentially thereof and laterally, a clamping member coextensive with the opening and pivoted at one end for swinging movement, gripping means on the inner side of said member to confront and bite a drilling tool when within the sleeve, means for holding the said clamping member within the opening, and a binding element mounted in the sleeve diametrically opposite the clamping member to coact with the gripping means for forcing these in biting engagement with the drilling tool, the said sleeve in its upper portion being formed with a plurality of radially disposed sockets and operating bars interchangeably engaging in said sockets. 90 95 100 105

In testimony whereof I affix my signature. 110
VACLAV PRAJER.
